CLAIM

The ornamental design for a washing machine, as shown and described.

DESCRIPTION

FIG. 1 is a front perspective view of a washing machine, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion 8 in FIG. 1;

FIG. 9 is an enlarged view of the encircled portion 9 in FIG. 2; and,

FIG. 10 is an enlarged view of the encircled portion 10 in FIG. 4.

The dot-dot-dash broken lines encircling enlargement portions of the design form no part of the claimed design.

(Continued)

The evenly dashed broken lines in the figures depict portions of the washing machine and form no part of the claimed design.
